UNITED STATES PATENT OFFICE.

HARRY T. GOSS, OF RUTHERFORD, NEW JERSEY, ASSIGNOR TO GEORGE H. FROTHINGHAM CO., OF NEW YORK, N. Y., A CORPORATION OF NEW YORK.

FERRY-LANDING MECHANISM.

1,160,506.

Specification of Letters Patent. Patented Nov. 16, 1915.

Application filed July 29, 1913. Serial No. 781,771.

To all whom it may concern:

Be it known that I, HARRY T. Goss, a citizen of the United States, and a resident of Rutherford, Bergen county, and State of New Jersey, have invented certain new and useful Improvements in Ferry-Landing Mechanism, of which the following is a specification, reference being had to the accompanying drawings, forming a part thereof.

My invention relates to ferry landings and docks, and particularly to such as are provided with pivoted gang-plank structures.

One object of my invention is to provide a simple and durable mechanism for securing a gang-plank in its elevated position, of such a character that it may be readily released from the deck of a boat without any assistance from a deckhand or other attendant on the shore.

Other objects and advantages will be set forth hereinafter.

I will describe my invention in the following specification, and then point out the novel features thereof in appended claims.

Referring to the drawings: Figure 1 is an elevation of a ferry landing showing a portion of a ferryboat which is secured thereto. A side elevation on a larger scale of the gang-plank in its elevated position is shown in Fig. 2. Figs. 3 and 4 are respectively a plan view and an elevation looking at its outer end of the gang-plank of Fig. 2. Figs. 5 and 6 are views corresponding respectively to Figs. 2 and 3 except that the plank is in its lowered position, of a modified structure embodying a sliding weight in addition to the toggle of the previous figures. Still other modifications of structure both of which embody my invention are shown in Figs. 7 and 8 which are views corresponding to Fig. 5.

Like characters of reference designate corresponding parts in all the figures.

Referring to Figs. 1 to 4 inclusive of the drawings, 10 represents the lower deck and 11 the upper deck of a ferry bridge, 12 being a gangway which is pivotally connected at 13 to the upper deck 11 and to 14 which is secured a pivoted gang-plank. The pivoted gang-plank with which my present invention is principally concerned is adapted to occupy an elevated position as shown in Fig. 2, in which it is supported as hereinafter explained, and a lowered posi-

tion as shown in Fig. 1 and in dotted lines in Fig. 2, when its outer end rests on the deck of a boat. The gang-plank is pivoted at 20 near the outer end of the gangway 12 and is either provided with a counterweight such as 19, or is otherwise so constructed as to be substantially balanced in order that it may be very readily swung from its lowered to its elevated position or vice versa. Various means may be employed for holding the plank in its elevated position within the spirit and scope of my invention. For purposes of illustration I have chosen four different arrangements, the first of which is illustrated in Figs. 1 and 4 and comprises an overset toggle and a suitable releasing lever, and the second of which is shown in Figs. 5 and 6, and comprises an arrangement similar to the first, except that a sliding weight is added. A third arrangement consists of a weight and positive means for shifting the position of the weight so as to overbalance the plank in one direction or the other according as it is found desirable to raise or lower the plank. The fourth arrangement is similar to the third except that the arrangement of parts is such that a single weight acts automatically to hold the bridge in the position to which it may be adjusted. In the first arrangement the toggle referred to comprises links 21 which are pivotally connected to the gangway 12 at 22, and a link 23 which is pivotally connected to the gang-plank at 24 near its outer end and is joined to the links 21 at 25. The link 23 is provided with a hook-shaped projection 26 which is adapted to engage a pin 27 on the links 21, when the gang-plank is in its elevated position and the toggle is overset. A bell crank lever 30 is also pivoted at 24 and is adapted to release the toggle, a pin 31 being provided at one end to engage the link 23 near the point 25 and the opposite arm of the lever being provided with a handle 32 which may be grasped by the hand of an attendant. When a ferry boat such as 15, comes up to the ferry bridge an attendant standing on the upper deck of the boat grasps the handle 32 and pulls the bell crank lever 30 toward him. The action of the pin 31 against the link 23 then serves to break the toggle joint and release the plank which may readily be pushed downward to its lowered position or allowed to fall if the outer end is made slightly 110

heavier than its inner end. When the boat is leaving the bridge the attendant stands on the boat as before and lifts the gang-plank at its outer end, the toggle being moved into its set position automatically as shown in Fig. 2.

Referring now to Fig. 5 the arrangement here shown comprises the same parts which already have been described in connection with the structure of Fig. 2, but in addition, a weight 40 is mounted to slide on a rod or bar 41 which is attached to the gang-plank structure and is so placed that it is inclined slightly to the horizontal in one direction or the other according as the bridge occupies its lowered or its elevated position. This is clearly illustrated in the drawings and obviously the weight 40 slides from one end, to the other of the rod or bar as the position of the plank is changed. This arrangement has the advantage of permitting the plank itself to be very closely balanced while at the same time it has a tendency to remain in the position to which it is adjusted. In fact, the sliding weight may be utilized alone and the toggle and release mechanism omitted entirely. In this case the weight is depended upon for holding the plank in its elevated position until it is pulled down by an attendant on the boat. The weight may be pivotally supported at the point 20 instead of being slidably mounted as shown in Fig. 5. This arrangement is shown in Fig. 7, the position of the pivoted weight 45 being determined by a lever 46 which is pivoted at 47 near the end of the gang-plank and is connected to the weight arm 48 by a link 49. When the weight is thrown back as shown in dotted lines in Fig. 7, the gang-plank tends to occupy its elevated position and when the weight is moved forward as is the case when the attendant on the deck of the boat pulls the lever 46, the plank falls to its lowered position. The rotative movement of the weight about the point 20 as a pivot, may be limited by any suitable means such as pins or stops 44.

As shown in Fig. 8 a weight 50 is suspended by a chain or cable 51 from a point 52 which is directly over the point of pivot 20 of the gang-plank when the plank is midway between its elevated and lowered positions and moves to one side or the other of this position according to the position of the plank. The weight may be suspended directly from the point 52 but I prefer to interpose the guide sheaves or pulleys 53-54 in order to prevent a swinging movement of the weight in response to movements of the gang-plank. The location of the guide pulley 53 is such that the chain or cable 51 extends through the point of pivot 20 of the plank when the plank is midway between its extreme positions. With this arrangement it is only necessary for

the attendant standing on the deck of the boat to pull down the plank or raise it to its elevated position as the case may be. According to the usual practice the outer end of the gang plank 14 may be provided with 70 a pivoted toe or flap 14^a which insures a closer fit between the end of the gang plank and the deck of the boat.

The mechanisms illustrated may be provided only at one side of a gang plank or 75 may be partially duplicated on the respective sides of the gang plank as shown in Fig. 6. Other modifications and combinations of the arrangements illustrated will suggest themselves to those skilled in the 80 art and I intend that only such limitations shall be imposed as are indicated in the appended claims.

What I claim is:

1. A ferry landing mechanism comprising 85 a pivoted gang-plank adapted to occupy an elevated position and a lowered position, a toggle for supporting the plank in one of its said positions, and means for releasing the toggle to permit the plank to move to its 90 lowered position.

2. A ferry landing mechanism comprising 95 a pivoted gang-plank adapted to occupy an elevated position and a lowered position, a toggle for supporting the plank in its elevated position, and means operable from the deck of a boat at the outer end of the plank for releasing the toggle to permit the plank to move to its lowered position.

3. A ferry landing mechanism comprising 100 a pivoted gang-plank adapted to occupy an elevated position and a lowered position, a toggle for supporting the plank in its elevated position, and a pivoted lever operatively connected with the toggle adapted to 105 release said toggle to permit the plank to move to its lowered position.

4. A ferry landing mechanism comprising 110 a pivoted gang-plank adapted to occupy an elevated position and a lowered position, 115 a pair of toggle links connected with said plank adapted to be self-sustaining to hold the plank in its elevated position when said links are overset in one direction, and a bell crank lever operatively connected with the toggle links adapted to release the links to permit the plank to move to its lowered position.

5. A ferry landing mechanism comprising 120 a pivoted gang-plank adapted to occupy an elevated position and a lowered position, and a rod or bar which is substantially horizontal when the plank is midway between the aforesaid positions, and a weight 125 slidably mounted on the rod or bar and adapted to overbalance the plank in one direction or the other and so hold it in the position to which it is adjusted.

6. A ferry landing mechanism comprising 130 a pivoted gang-plank adapted to occupy an

10 elevated position and a lowered position, a toggle for supporting the plank in its elevated position, means for releasing the toggle to permit the plank to move to its lowered position, and a weight operatively connected with the gang-plank and adapted to be moved automatically in response to a change in the position of the gangplank to overbalance the plank and so hold it in the position to which it is adjusted.

15 7. A ferry landing mechanism comprising a pivoted gang-plank adapted to occupy an elevated position and a lowered position, a toggle for supporting the plank in its elevated position, means operable from the deck of a boat at the outer end of the plank for releasing the toggle to permit the plank to move to its lowered position, and a means connected with the gang-plank for movably supporting the weight, said means being arranged to allow the weight to shift its position automatically when the position of the bridge is changed to overbalance the plank and so hold it in the position to which it is adjusted.

20 8. A ferry landing mechanism comprising a pivoted gang-plank adapted to occupy an elevated position and a lowered position, a toggle for supporting the plank in its elevated position, a pivoted lever connected with the toggle adapted to release said toggle to permit the plank to move to its lowered position, a weight connected with the gang-plank and adapted to be moved in response to a change in the position of the gangplank to overbalance the plank and so hold it in the position to which it is adjusted.

25 9. A ferry landing mechanism comprising a pivoted gang-plank adapted to occupy an elevated position and a lowered position, a toggle for supporting the plank in its elevated position, means for releasing the toggle to permit the plank to move to its low-

ered position, a rod or bar which is substantially horizontal when the plank is midway between the aforesaid positions, and a weight slidably mounted on the rod or bar and adapted to overbalance the plank in one direction or the other and so hold it in the position to which it is adjusted.

30 10. A ferry landing mechanism comprising a pivoted gang-plank adapted to occupy an elevated position and a lowered position, a toggle for supporting the plank in its elevated position, means operable from the deck of a boat at the outer end of the plank for releasing the toggle to permit the plank to move to its lowered position, a rod or bar which is substantially horizontal when the plank is midway between the aforesaid positions, and a weight slidably mounted on the rod or bar and adapted to overbalance the plank in one direction or the other and so hold it in the position to which it is ad- 35 justed.

35 11. A ferry landing mechanism comprising a pivoted gang-plank adapted to occupy an elevated position and a lowered position, a toggle for supporting the plank in its elevated position, a pivoted lever connected with the toggle adapted to release said toggle to permit the plank to move to its lowered position, a rod or bar which is substantially horizontal when the plank is midway between the aforesaid positions, and a weight slidably mounted on the rod or bar and adapted to overbalance the plank in one direction or the other and so hold it in the position to which it is adjusted.

40 In testimony whereof, I have hereunto set my hand in the presence of two subscribing witnesses, this 26 day of July, 1913.
